ANIMAL CRATE

John Laurence Hufiesen, 2446 Catalpa Drive, Dayton,
Ohio, and Carl H. Clement, Jr., 3600 Summit St.,
Toledo, Ohio

Filed July 18, 1960, Ser. No. 61,409

Term of patent 14 years

(Cl. D12—2)

FIG-1

FIG-2

FIG-3

FIG-4

FIG-5

FIG-6

Figure 1 is a top plan view of an animal crate showing our new design.

Figure 2 is a side elevational view.

Figure 3 is a bottom view.

Figure 4 is a front view.

Figure 5 is a rear view.

Figure 6 is a perspective view, showing the door of the animal crate in an open position.

We claim:

The ornamental design for an animal crate, substantially as shown.
